UNITED STATES PATENT OFFICE.

JOSEPH McNELLY, OF COLLINGSWOOD, NEW JERSEY, ASSIGNOR TO UNION SPECIAL MACHINE COMPANY, OF CHICAGO, ILLINOIS, A CORPORATION OF ILLINOIS.

FOLDING AND GUIDING DEVICE.

1,082,351.

Specification of Letters Patent.

Patented Dec. 23, 1913.

Application filed August 10, 1905. Serial No. 273,572.

To all whom it may concern:

Be it known that I, JOSEPH McNELLY, a citizen of the United States, residing at Collingswood, in the county of Camden, State of New Jersey, have invented certain new and useful Improvements in Folding and Guiding Devices, of which the following is a description, reference being had to the accompanying drawing and to the letters and 10 figures of reference marked thereon.

My invention relates to an improvement in folding devices for sewing machines, and particularly to a folding and guiding device for use in connection with the Union Special 15 yoke ruffling machine, such as illustrated in Patent 655,143, issued July 31st, 1900, to R. G. Woodward.

The object of the present invention is to provide a device which shall fold and guide 20 the body portion of a shirt, fold and guide the top layer of the yoke of the shirt, and guide the bottom layer of the yoke of the shirt, so that when the latter is turned over on the stitching as a hinge, the under side 25 of the lines of stitching will be concealed from view, covered by the bottom layer of the yoke.

In the usual construction of folding devices for use in connection with machines for 30 securing the layers of the yoke to the body portion, no means have been provided for folding the edge of the body portion of the fabric, and, therefore, under strain, the raw edges thereof will pull out. By the present 35 arrangement, however, this is prevented.

The invention, therefore, consists in the various matters hereinafter described and referred to in the appended claims.

The invention is illustrated in the accompanying drawings, in which—

Figure 1 is a perspective view of a folder constructed in accordance with my invention; Fig. 2 is a cross section; and Fig. 3 is a perspective view showing the relation of 45 the layers of fabric as they leave the folding and guiding devices.

The machine upon which this folder is intended to be used, is similar to that illustrated in the patent above referred to; it is 50 intended to use two lines of stitching for uniting the fabrics, as shown in Fig. 3, but it will be understood that it may be applied to a single needle machine, as well.

As shown in these drawings, A represents 55 the base piece of the folding device adapted

to be secured to the bed plate of the sewing machine in the usual way. It has secured to it a piece B, having a horizontally projecting portion C, extending over the base piece, and forming a recess a to receive and 60 guide the under layer 1 of the yoke. Projecting upwardly from the top face of this piece B is a scroll D, which serves to fold and guide the edge of the body 2, of the fabric, the edge of which is to be ruffled, and 65 folded and secured to the upper and lower layers of the yoke. It will be noted that the recess a extends to the right of the scroll D as viewed in Fig. 2. The purpose of extending this recess a beyond the body of the scroll is to guide the edge of the unfolded 70 fabric, so that the same will extend well beyond the line of the seam and be properly secured by said seam.

Adjustably secured upon the right hand 75 upper face of the piece B, by means of a co-operating feather and guide way 4, 5, and adjusting screws 6, is an angular plate E formed with a fabric rest and guide F, and pressing tongue 7, and having secured to it 80 a scroll G, to fold and guide the edge of the upper layer 3, of the yoke. By adjusting this angular plate, the position of the fold in the upper layer, with respect to that in the lower one, may be varied. 85

As indicated, the lower layer of the yoke is inserted in the recess a, the body fabric in the folding and guiding scroll D, and the upper layer of the yoke, in the folding and guiding scroll G. The goods are then ruffled 90 and stitched, by the two rows of stitching, and the lower layer 1, folded back on the lines of stitching as a hinge, making the fabric complete.

Having thus described my invention, 95 what I claim as new and desire to secure by Letters Patent, is:—

1. A folding and guiding device for sewing machines having a guiding recess for a lower layer of fabric, a folding member 100 above the same for the body fabric, said folding member comprising an upper, laterally and downwardly extending portion adapted to fold an edge upon the body fabric, a second oppositely placed folding 105 and guiding member having a guiding scroll for guiding and folding the edge of an upper layer of fabric, a rest plate carried by and projecting laterally from said guiding scroll for supporting the fabric being folded 110

by said scroll and a pressing tongue for engaging and holding the fabrics as they leave the folder.

2. A folding and guiding device for sewing machines having a guiding recess for a lower layer of fabric, a folding member above the same for the body fabric, said folding member comprising an upper, laterally and downwardly extending portion 10 adapted to fold an edge upon the body fabric, a second oppositely placed folding and guiding member having a guiding scroll for guiding and folding the edge of an upper layer of fabric, a rest plate carried by 15 and projecting laterally from said guiding scroll for supporting the fabric being folded by said scroll, and means whereby said second folding and guiding member may be adjusted with respect to said first folding member.

3. A folding and guiding device for sewing machines, having a guiding recess for a lower layer of fabric, a folding scroll for the body fabric located above said recess and facing in the same direction, said folding scroll comprising an upwardly, laterally and downwardly extending portion 25 adapted to fold the edge of the body fabric, said guiding recess extending laterally to a point beyond said guiding scroll and a second oppositely placed folding and guiding member having means for guiding and folding the edge of an upper layer of fabric.

4. A folding and guiding device for sewing machines, having a guiding recess for the lower layer of fabric, a folding member above the same for the body fabric, said folding member comprising an upwardly, laterally and downwardly extending por-

tion adapted to fold an edge upon the body 40 fabric, and a second oppositely placed folding and guiding member having a guide scroll for guiding and folding the edge of an upper layer of fabric, and a pressing tongue for engaging and holding the fabrics as they leave the folders.

5. A folding and guiding device for sewing machines, comprising a base piece, a piece secured thereto, and having a horizontally projecting portion parallel with the 50 base piece and forming a recess α between the two, a scroll D, secured to said piece and having its receiving recess opening in the same direction as the recess α whereby the layer of fabric passing the scroll D is 55 superimposed upon the layer of fabric guided by the recess α , and an angular plate also secured to said piece and carrying a scroll oppositely placed from the scroll D; substantially as described.

6. A folding and guiding device for sewing machines, comprising a base piece, a piece secured thereto, and having a horizontally projecting portion parallel with the 65 base piece and forming a recess α between the two, a scroll D, secured to said piece, and an angular plate also secured to said piece and carrying a scroll oppositely placed from the scroll D, said angular plate being adjustable on said piece; substantially as 70 described.

In testimony whereof I affix my signature, in presence of two witnesses.

JOSEPH McNELLY.
